SHIPPING CONTAINER

Willis F. Luce, San Francisco, and Clarence C. Kennedy, Palo Alto, Calif., assignors to Owens-Illinois Pacific Coast Company, a corporation of Delaware

Application May 11, 1938, Serial No. 207,188

12 Claims. (Cl. 229—6)

The improved shipping container comprising the present invention is primarily adapted for use as a returnable shipping case for beer bottles and soft drink bottles which makes repeated outgoing trips from the brewery or bottling works with the filled bottles therein and which is returned with the empty bottles therein. The principles of the invention are however applicable to other uses and the container may be employed wherever a rugged and durable shipping case that will withstand rough usage is required.

In the distribution of beer, particularly local truck distribution of bottled beer from the brewery to the consumer, a shipping container that will withstand hard usage and repeated abuse is essential to economy of handling operations. While the use of a closed substantially sealed carton type of shipping container is most desirable from the standpoint of light-exclusion from and heat insulation of the bottled product and from the standpoint of protection of the bottles, the rapid deterioration of shipping containers of this type has resulted in the general use of open wooden shipping cases which possess neither insulating qualities nor light exclusion features. Such wooden cases however are rugged and consequently more durable. They are not subject to decomposition when the bottles are placed therein upside down so that the residual liquid is spilled therein as is frequently the case. They may stand on wet floors or in wet places without danger of the bottoms thereof decomposing and they may be given reasonably rough treatment in use. Such wooden cases however are not ideal mainly because they are expensive and although they are more durable than the closed carton type of container they are subject to ultimate deterioration due of the effects of scuffing, denting, splitting, chipping, weathering and staining. Furthermore such wooden cases are extremely heavy and contribute materially to the breakage of bottles when the cases are stacked high in the warehouse with the filled bottles therein or when they are filled with empty bottles and piled together by the consumer. In addition to the above noted objections, wooden cases are rigid, and since space must be allowed for ready insertion and removal of the bottles from the compartments provided therein, the bottles are free to rattle in their individual compartments, thus further contributing to bottle destruction as well as contributing materially to the waste space re-

quired in the shipping of the bottles. Finally such wooden cases, even though they may remain intact after many repeated trips to and from the brewery, rapidly acquire a shabby appearance and are discarded often for that reason alone. 5

The principal object of the present invention is to provide a carton type container suitable for the distribution of beer which will overcome the above mentioned limitations that are attendant upon the common carton type of container and upon the wooden shipping case by providing a rugged and durable rigid skeleton or frame work to which there is applied a covering of carton material which may be removed and replaced at will. Such a container is capable of excluding light from the bottled product; is heat insulating; is reinforced, and therefore is stronger than the common variety of carton container and will withstand rougher usage while at the same time the skeleton or framework thereof is protected from denting, splitting, chipping, etc., as outlined above. 10 15

Another object of the invention is to provide a shipping container of the type set forth above which particularly overcomes the serious objection presented by leakage from inverted bottles. Toward this end the invention contemplates the provision of a framework which itself forms both a bottom upon which the bottles may rest and a bottom by means of which the container as a whole may rest upon its supporting surface. Thus the container is subject neither to decomposition due to internal leakage of liquid nor to decomposition due to its standing in a 20 25 30 35 wet place.

The provision of a shipping container including a skeleton or framework and an outer removable covering and closure therefor which covering may readily and easily be replaced after a period 40 of use; a container which is attractive in appearance; one which differs but little in style from the conventional carton type of container and which therefore is readily acceptable as such; one which will take on an appearance of newness 45 each time replacement of the covering is effected; one in which the replacement may be performed at a very low cost; one which is comparatively light despite its ruggedness and durability; one in which attachment of the covering to the skeleton 50 or framework requires no fastening means on the latter nor mutual fastening means between the two; one in which the covering affords protection to the skeleton or framework both from the outside and from within; one in which the covering 55

may be formed from a single sheet of blank material; and one which is well adapted to perform the services required of it, are further desiderata that have been borne in mind in the production and development of the present invention.

Other objects and advantages of the invention, not at this time particularly enumerated, will become readily apparent as the nature of the invention is better understood.

10 In the accompanying drawings four embodiments of the invention are disclosed. In these drawings:

Fig. 1 is a perspective view of the improved shipping container showing the same open.

15 Fig. 2 is a perspective view of the skeleton or framework thereof.

Fig. 3 is a transverse sectional view taken vertically through the container.

Fig. 4 is a side elevational view of the container 20 with certain parts thereof being broken away and other parts thereof being shown in section to more clearly reveal the nature of the invention.

Fig. 5 is a plan view of a blank from which the removable covering is formed.

25 Fig. 6 is a perspective view of a modified form of sheet metal framework or skeleton for the container.

Fig. 7 is a transverse sectional view taken vertically through the framework of Fig. 6 showing 30 the covering applied thereto.

Fig. 8 is a perspective view of a blank from which the covering of Fig. 7 is formed.

Fig. 9 is a transverse sectional view taken vertically through another modified form of container 35 with certain parts broken away, and

Fig. 10 is a sectional view similar to Fig. 9 showing yet another modified form of container.

The container shown in Figs. 1 to 5 inclusive involves in its general organization a rigid open 40 box-like skeleton or framework 10 which comprises a foundation for the container and which includes side walls 11 and 12, end walls 13 and 14, and a bottom 15. While the framework 10 may be of any suitable size and of any suitable 45 material, in the present instance it is preferably of a size that will accommodate a case or twenty-four beer bottles of the ordinary 16 oz. variety and is preferably formed of wood on account of the lightness, strength, durability and low cost of the latter. The end walls 13 and 14 50 may be made considerably thicker than the side walls 11 and 12 as is the custom in the art of box making to avoid splitting of the wood when the fastening nails for the side walls are driven 55 thereto and also to lend rigidity to the structure. The bottom 15 may also be thicker than the side walls 11 and 12 since the bottom forms a direct support for the assembled container and is subject to abrasion by scuffing or otherwise 60 when handling.

The width of the bottom 15 is slightly less than the width of the end walls 13 and 14 and likewise the width of the wooden side walls 11 and 12 is slightly less than the width of the end walls 13 and 14 in the direction of their height. The upper edges of the side walls 11 and 12 terminate flush with the upper edges of the end walls 13 and 14 while the longitudinal edges of the bottom 15 are spaced inwardly a short distance from the 65 vertical edges of the end walls 13 and 14. Thus longitudinal gaps 16 or slots are provided along the lower longitudinal edges of the structure for a purpose that will presently appear.

70 The replaceable covering 20 is formed from a single blank of conventional fiberboard carton

material which is generally of rectangular configuration as shown in Fig. 5 and is provided with transverse crease lines 22, 23 and 24 dividing the blank into end panels 25 and 27 and side panels 26 and 28. The panels 25, 26, 27 and 28 are 5 adapted to coextensively overlie and cover the outside surfaces of respective side and end walls 11, 12, 13 and 14 of the skeleton or framework 10. The blank may be wrapped, so to speak, about these side and end walls of the framework 10 and in order to fasten the ends of the blank together 10 a crease line 21 adjacent one end of the blank provides an attachment tab 29 which underlies a portion of the side panel 28 on the side wall 12 of the framework 10, and which may be fastened thereto in any suitable manner as for example by means of fastening pins 30 or staples.

A pair of longitudinal crease lines 31 and 32 provide a pair of elongated narrow tongues 33 and 34 respectively which project from the side panels 26 and 28 and which are adapted to be bent at right-angles thereto inwardly of the container and are received in the gaps 16 provided between the lower edges of the side walls 11 and 12 and the opposed longitudinal edges of the bottom 15 of the framework 10. Thus the covering 20 is prevented from shifting bodily upwardly when in position on the framework.

A pair of parallel crease lines 40 and 41 provide a narrow elongated top panel 42 which forms 30 a covering for the upper edge of the end wall 14 of the framework 10 when the panel 42 is bent inwardly of the container at right-angles to the end panel 25. Similarly a pair of parallel crease lines 43 and 44 provide a narrow elongated top 35 panel 45 forming a covering for the upper edge of the end wall 13 of the framework 10.

Panels 47 and 48 of reduced width join the panels 42 and 45 respectively along the respective crease lines 41 and 44 and are adapted to be bent 40 at right-angles to the narrow panels 42 and 45 so as to extend parallel to the end panels 25 and 27 and partially cover the inner surfaces of the end walls 13 and 14 of the framework 10. Panels 50 and 51 join the panels 26 and 28 respectively 45 along respective longitudinal crease lines 52 and 53 and when bent at right-angles to these latter panels extend inwardly across the top of the container toward each other to provide a closure therefor. A pair of crease lines 54 and 55 respectively provide a pair of elongated retaining tongues 56 and 57 which are adapted to be bent at right-angles to the panels 50 and 51 and brought 50 into coextensive surface contact with each other and projected downwardly into the container centrally thereof between the end walls 13 and 14 of the framework 10. The length of the tongues 56 and 57 is substantially equal to the distance 55 between the inside surfaces of the end walls 13 and 14 and in order to permit these tongues to be 60 so projected downwardly between the end walls, slots 60 are formed in the blank transversely thereof in the vicinity of the juncture between the panels 47, 42, and 48, 45 respectively. The inner 65 ends of the slots 60 formed in the blank are flared as at 61 to provide guiding means for the edges of the tongues 56 and 57, thus facilitating sealing or closing of the container package. The length of the panels 50 and 51 is substantially the overall 70 length of the container and thus when these panels are brought into alignment in a common plane and provide a closure for the container, they find support on the panels 42 and 45 which overlie and cover the upper edges of the end walls 13 and 14 of the framework 10.

Hand holes 62 are formed in the end walls 13 and 14 and similar hand holes 63 provided in the panels 25 and 27 register therewith when the covering is assembled upon the framework.

Referring now to Figs. 6, 7 and 8, wherein a modified form of shipping container is disclosed, the skeleton or framework 70 in this instance is constructed of light sheet-metal which is sufficiently rigid to withstand the rough usage expected of it. The framework 70 includes side walls 11 and 12, end walls 13 and 14, and a bottom 75. The side walls and bottom are formed from an integral sheet of metal, the former existing by virtue of a reversal of the material upon itself to provide the side walls of double thickness. The longitudinal edges of the sheet are flanged outwardly and upwardly in the vicinity of the lower longitudinal edges of the framework to provide a pair of retaining flanges 76. The lower transverse edges of the end walls 13 and 14 are similarly flanged to provide retaining flanges 77. The end walls 13 and 14 are spot welded as at 78 to the ends of the side walls 11 and 12.

The replaceable covering 79 is in many respects identical with the covering 20 in the form of the invention previously described and like characters of reference have been employed to designate corresponding parts thereof. The main point of departure from the almost identical covering 20 resides in the omission of the tongues 33 and 34 which are unnecessary and undesirable in view of the fact that the lower longitudinal edges of the panels 26 and 28 at which these tongues would ordinarily occur are received in the retaining flanges 76 while the lower edges of the panels 25 and 27 are received within the retaining flanges 77 when the covering 79 is assembled upon the framework 70.

Another point of departure resides in the provision of hand holes 80 in the panels 47 and 48 which register with the hand holes 62 formed in the end walls 13 and 14 and with the hand holes 63 formed in the panels 25 and 27 when the covering 79 is assembled on the framework 70.

The form of the invention just described is particularly well adapted to afford protection to the covering when the container stands in a wet place. Furthermore the covering 79 is not subject to wetting when empty bottles are placed therein upside down. The retaining flanges 76 and 77 surround the lower edges of the side and end panels 26, 28, and 25, 27, completely and protect the same from contamination. On the inside of the container, no portion of the covering 79 extends below a plane several inches above the framework bottom 75 and consequently the lower edges of the covering are in no danger of being contaminated by liquid that may have spilled within the container.

Referring now to Figs. 9 and 10, two additional modified forms of shipping containers are shown. Both of these containers utilize skeletons or frameworks which are identical with the ones shown in Fig. 2 and for convenience the same reference characters have been applied to the corresponding parts thereof.

In the form of the invention shown in Fig. 9, the covering 100 is formed from a single blank of carton material and includes inner side panels 101 and 102 which are coextensive with the inner sides of the side walls 11 and 12 respectively; inner end panels 103 which partially cover the inner sides of the end walls; elongated bottom panels 104 and 105 which are coextensive with

the lower edges of the side walls; outer side panels 106 and 107 which are coextensive with the outer sides of the side walls 11 and 12; elongated top panels 108 which are coextensive with the upper edges of the end walls 13; outer end panels 109 substantially coextensive with the outer sides of the end walls 13; and cover panels 110 and 111 which are adapted to occupy the same common plane and close the open end of the framework. The width of the inner end panels 103 is slightly less than the width of the end walls 13 and thus these end panels may be wedged in between the two inner side panels 101 and 102 and consequently will be retained in proper position.

In the form of the invention shown in Fig. 10, the covering 119 is formed from a single blank and includes inner side panels 120 and 121 which partially cover the inner sides of the side walls 11 and 12; inner end panels 123 which partially cover the inner sides of the end walls 13; elongated top panels 124 and 125 which are coextensive with the upper edges of the side walls; outer side panels 126 and 127 which completely cover the outer sides of the side walls; outer end panels 128 which substantially cover the outer sides of the end walls 13; elongated top panels 129 which are coextensive with the upper edges of the end walls; and inwardly extending tongues or panels 130 and 131 which project through the gaps 16 and lie along the bottom 15 with adjacent edges thereof substantially meeting each other.

It is to be understood that the fastening means employed in securing the coverings 100 and 119 of Figs. 9 and 10 respectively is substantially the same as has been illustrated and described in connection with the form of the invention shown in Figs. 1 to 5 inclusive.

The invention is not to be limited to the exact arrangement of parts shown in the drawings or described in the specification as various changes in the details of construction are contemplated. For example, while fastening staples have been illustrated for holding the outer coverings on the various frameworks, other fastening means may be employed. Only insofar as the invention has particularly been pointed out in the appended claims is the same to be limited.

We claim:

1. A shipping container comprising in combination a box-like framework having an open top and including opposed side walls, opposed end walls, and a bottom; a removable covering on said framework including panels substantially covering the outer sides of the side and end walls, the upper edges of the end walls, and the inner sides of the end walls; and cooperating means on said framework and covering for preventing upward shifting of the latter on the former.

2. A shipping container comprising in combination a box-like framework having an open top and including opposed side walls, opposed end walls, and a bottom; a removable covering on said framework including panels substantially covering the outer sides of the side and end walls, the upper edges of the end walls, and the inner sides of the end walls; and means for fastening one of the panels which covers the outer side of an end wall to one of the panels which covers the outer side of a side wall.

3. A shipping container comprising in combination a box-like framework having an open top and including opposed side walls, opposed end walls, and a bottom; a removable covering on said framework including panels substantially

covering the outer sides of the side and end walls, the upper edges of the end walls, and the inner sides of the end walls; cooperating means on said framework and covering for preventing upward shifting of the latter on the former; and means for fastening one of the panels which covers the outer side of an end wall to one of the panels which covers the outer side of a side wall.

4. A shipping container comprising in combination a box-like framework having an open top and including opposed side walls, opposed end walls, and a bottom; a one-piece removable covering on said framework including outer end, top, and inner end panels which are hinged together and which cover the outer side, the upper edge, and the inner side respectively of each end wall, an outer side panel hinged to both outer end panels and covering the outer side of one of said side walls, a second outer side panel hinged to one of said outer end panels and covering the outer side of the other side wall; and means for fastening said second outer side panel to the other outer end panel.

5. A shipping container comprising in combination a box-like framework having an open top and including opposed side walls, opposed end walls, and a bottom; a one-piece removable covering on said framework including outer end, top, and inner end panels which are hinged together and which cover the outer side, the upper edge, and the inner side respectively of each end wall, an outer side panel hinged to both outer end panels and covering the outer side of one of said side walls, a second outer side panel hinged to one of said outer end panels and covering the outer side of the other side wall; cooperating means on said framework and outer side panels for preventing upward shifting of the covering on the framework; and means for fastening said second outer side panel to the other outer end panel.

6. A shipping container comprising in combination a box-like framework having an open top and including opposed side walls, opposed end walls, and a bottom; a one-piece removable covering on said framework including outer end, top, and inner end panels which are hinged together and which cover the outer side, the upper edge, and the inner side respectively of each end wall, an outer side panel hinged to both outer end panels and covering the outer side of one of said side walls, a second outer side panel hinged to one of said outer end panels and covering the outer side of the other side wall; cooperating means on said side walls, bottom and outer side panels for preventing upward shifting of the covering on the framework; and means for fastening said second outer side panel to the other outer end panel.

60 7. A shipping container comprising in combination a box-like framework having an open top and including opposed side walls, opposed end walls, and a bottom, the lower edges of said side walls being spaced from the edges of said bottom to provide a gap therebetween; a one-piece removable covering on said framework including outer end, top, and inner end panels which are hinged together and which cover the outer side, the upper edge, and the inner side respectively of each end wall, an outer side panel hinged to both outer end panels and covering the outer side of one of said side walls, a second outer side panel hinged to one of said outer end panels and covering the outer side of the other side wall; and a tongue formed on each of said outer side panels,

said tongues extending into said gaps to retain the covering on the framework and prevent upward shifting of the same thereon.

8. A shipping container comprising in combination a box-like framework having an open top and including opposed pairs of walls and a bottom; a one-piece removable covering on said framework including outer, top, and inner panels which are hinged together and which cover the outer side, the upper edge, and the inner side respectively of each wall of one of said pairs; a panel hinged to both of said outer panels and covering the outer side of one wall of the other pair, a panel hinged to one of said outer panels, and means for fastening said last mentioned panel to the other outer panel.

9. A shipping container comprising in combination a box-like framework having an open top and including opposed side walls, opposed end walls, and a bottom; a one-piece removable covering on said framework including outer end, top, and inner end panels which are hinged together and which cover the outer side, the upper edge, and the inner side respectively of each end wall, an outer side panel hinged to both outer end panels and covering the outer side of one of said side walls, a second outer side panel hinged to one of said outer end panels and covering the outer side of the other side wall, and a cover panel hinged to each of said outer side panels.

10. A shipping container comprising in combination a box-like framework having an open top and including opposed side walls, opposed end walls, and a bottom; a one-piece removable covering on said framework including outer end, top, and inner end panels which are hinged together and which cover the outer side, the upper edge, and the inner side respectively of each end wall, an outer side panel hinged to both outer end panels and covering the outer side of one of said side walls, a second outer side panel hinged to one of said outer end panels and covering the outer side of the other side wall, a cover panel hinged to each of said outer side panels, and a tongue hinged to each cover panel, said tongues having corresponding surfaces thereof in coextensive contact on the inside of the container.

11. A shipping container comprising in combination a box-like framework having an open top and including opposed side walls, opposed end walls, and a bottom; a one-piece removable covering on said framework including outer end, top, and inner end panels which are hinged together and which cover the outer side, the upper edge, and the inner side respectively of each end wall, an outer side panel hinged to both outer end panels and covering the outer side of one of said side walls, a second outer side panel hinged to one of said outer end panels and covering the outer side of the other side wall, a cover panel hinged to each of said outer side panels, and a tongue hinged to each cover panel, said tongues having corresponding surfaces thereof in coextensive contact on the inside of the container, there being a slot in one of said inner end panels into which said tongues are adapted to extend.

12. A shipping container comprising in combination a box-like framework having an open top and including opposed side walls, opposed end walls, and a bottom; a one-piece removable covering on said framework including outer end, top, and inner end panels which are hinged together and which cover the outer side, the upper edge, and the inner side respectively of each end wall, an outer side panel hinged to both outer end

panels and covering the outer side of one of said side walls, a second outer side panel hinged to one of said outer end panels and covering the outer side of the outer side wall, a cover panel hinged to each of said outer side panels, and a tongue hinged to each cover panel, said tongues having corresponding surfaces thereof in co-

extensive contact on the inside of the container, there being a vertical slot in one of said inner end panels into which said tongues extend, the upper region of said slot being flared to provide a guiding means for insertion of said tongues.
